UNITED STATES PATENT OFFICE

EUGENE G. REISING, OF EAST HARTFORD, CONNECTICUT, ASSIGNOR OF ONE-FOURTH TO
ALVA C. WASHBURN, OF PITTSFIELD, MASSACHUSETTS

FIREARM

Application filed December 31, 1930. Serial No. 505,794.

My invention relates more particularly to that class of firearms having a stock adapted to be supported against a portion, as the shoulder, of a person operating the device, and an object of my invention, among others, is the production of a firearm of this type that shall be particularly simple in construction and in method of operation, while at the same time having efficiency to a marked degree both as to its operation and as to the safety of such operation.

One form of a firearm embodying my invention and in the construction and use of which the objects herein set out, as well as others, may be attained is illustrated in the accompanying drawings, in which—

Figure 1 is a view in lengthwise vertical section through the breech portion of a firearm on a plane denoted by the dotted line 1—1 of Figure 4, the front portion of the stock and rear portion of the barrel being shown.

Figure 2 is a view in side elevation of the same.

Figure 3 is a view in section on a plane denoted by the dotted line 3—3 of Figure 1.

Figure 4 is a similar view on a plane denoted by the dotted line 4—4 of Figure 1.

Figure 5 is another view in cross section on a plane denoted by the dotted line 5—5 of Figure 1.

Figure 6 is a view in horizontal section on a plane denoted by the dotted line 6—6 of Figure 1.

Figure 7 is an isometric view of the cartridge feed block.

Figure 8 is an isometric view of portions of the frame and breech bolt head with parts disconnected therefrom but shown in their relative positions.

My improved firearm is of the magazine type, that is, one in which a plurality of cartridges are placed to be successively fired and it is semi-automatic in that when the trigger is pulled firing takes place, the empty cartridge shell is ejected and another cartridge is inserted in the breech in the barrel, the parts then coming to rest until the trigger is again pulled. In firearms of this type heretofore made a removable magazine has

been employed from which the cartridges are raised and then pushed forward into the breech of the barrel. My improved firearm embodies a magazine tube extending forwardly underneath the rear end of the barrel and from which the cartridges are moved backwardly and then upwardly and then forwardly into the opening in the breech of the barrel, my improved loading mechanism being so constructed that this operation is satisfactorily performed in a manner not heretofore deemed possible in an automatic firearm.

Such a firearm is illustrated in the drawings herein in which the numeral 10 denotes the stock that may be of any suitable form and material and constructed to receive a frame 11, which parts are secured together as by means of screws in a manner that will be hereafter described. The stock 10 is recessed in an ordinary manner in its upper side to receive the frame and it is also recessed on the under side to receive a trigger guard plate 12 having the usual trigger guard projecting downwardly intermediate its ends. This plate is secured at its front end as by means of a screw extending upwardly into a lug 13 projecting downwardly from the frame 11 whereby the front end of the trigger guard is drawn into its recess in the stock and the frame is drawn downwardly to its seat in the stock.

A frame head 14 preferably round in cross-section is seated in a groove in the upper end of the frame at its back end, the groove being of a shape to fit the head. The head is supported at its rear end by the end of a recess in the stock 10. A head screw 15 projects through the back end of the frame into said head, thereby securing the latter firmly in place. A screw 16 passes from the under side of the trigger guard plate 12 through said plate and into a threaded recess in the screw 15, thereby securing both the rear ends of said plate and frame to the stock. A receiver 17 of generally round shape in cross section is mounted on the frame 11 to fit the groove in the upper surface thereof. This receiver is reduced at its rear end to form an annular lip to engage a

flange on the front end of the frame head, and as shown in Figure 1 of the drawings. A barrel 18 is secured in any suitable manner in a hole opening into the front end of the receiver, screw threads being shown herein for this purpose.

10 A hammer 19 of generally round shape in cross section is mounted to fit a recess 20 in the head 14 and to slide within a breech bolt chamber 21 extending lengthwise within the receiver 17. A firing spring 22 is located in a hollow stem extending within the head 14, said spring projecting into a recess in the rear end of the hammer 19. A spring sup-

15 porting pin projects into said spring from a screw threaded plug 23 that closes the rear end of a chamber in the head. The hammer stem 24 projects backwardly from the hammer through a guide opening 25 extending from the rear end of the recess 20, and a

20 guide 26 is secured to the outer end of said stem, said guide fitting the wall of a guide and spring chamber 27 hereinbefore mentioned and in which the spring 22 is located, as

25 shown in Figure 1 of the drawings.

A sear engaging notch 28 is formed in the hammer, in the structure herein shown, this notch consisting of an annular groove extending around the hammer.

30 A breech bolt 29 of generally round shape in cross section as to its upper portion and round at its rear end to fit within the breech bolt chamber 21 in the receiver 17 is mounted for sliding reciprocating movement in said chamber, normally resting against the forward end of said chamber in proximity to the rearward end of the barrel 18. A breech bolt spring 31 is mounted in a recess 32 constituting a groove extending lengthwise in 35 the upper edge of the receiver, a narrow slot forming lips constituting the mouth of said recess whereby the spring 31 is retained in place. The back end of the spring thrusts against the screw 15 that acts as an abutment, 40 and the forward end of the spring is seated against a shoulder behind the head of a plunger 33, said plunger comprising a stem to project backwardly into the spring. Said plunger is pressed against a lug 34 projecting 45 and the forward end of the spring is seated against a shoulder behind the head of a plunger 33, said plunger comprising a stem to project backwardly into the spring. Said plunger is pressed against a lug 34 projecting 50 downwardly from the under side of the breech bolt near its back end. The bolt is recessed on its under surface to create a loading web 35 extending lengthwise of the bolt, in the bottom and crosswise center of the recess, 55 the end of said web engaging the end of a cartridge for the purpose of forcing it into the opening in the barrel 18.

A firing pin 37 has at its rear end a tail 38, said p'n and its tail being located in a slot 60 extending lengthwise in the breech bolt at its upper side and downwardly across the end thereof. A retaining pin 39 extends across the slot in the breech bolt and into a slot in the firing pin for the purpose of retaining the latter in place while permitting a limited

lengthwise movement thereof. A firing pin spring 40 is located in a recess at the back of the breech bolt and thrusts against the tail 38 to hold the pin at the rearward limit of its movement. The tail holds the pin from 70 striking the barrel.

A cartridge feed block 41 of generally rectangular shape in cross section has a cartridge receiving chamber 42 comprising a projection at the upper back end of the block, and as shown in Figure 7 of the drawings. The upper side of the block is recessed on a curve to fit the under side of the receiver 17. The chamber is open at its upper side which opening is provided with retaining lips 43 on opposite sides of the chamber which lips terminate intermediate the ends of the chamber, thereby forming an opening 44 through which the enlarged rim of a cartridge shell may pass, the lips 43 being near enough together to prevent said rim from passing out of the rear end of the chamber. The forward wall of the chamber is tapered upwardly and forwardly to form a guide 45 to cause the nose of the cartridge to travel upwardly in position to enter the opening in the breech of the barrel.

The projection comprising the chamber 42 closely fits within a hole of the same shape in the bottom of the receiver, and a feed tube opening 46 extends from the front end of the feed block into the cartridge receiving chamber at the rear end thereof. 95

A cartridge feed tube 47 of ordinary construction has its rear end located in said opening, said tube containing the usual spring and plunger for forcing cartridges 48 out of the tube and into the chamber in the feed block, and as shown in Figure 1 of the drawings. 105 100

One of the lips 43 has a shoulder that forms an ejector 49 against which the rear end of a cartridge shell strikes when said shell is drawn out of the barrel by mechanism to be hereinafter described.

A sear 50 is pivotally mounted in a sear groove 51 extending diagonally upward in the side of the frame 11, and as shown in Figures 2 and 8 of the drawings, said sear being mounted on a pin 52 projecting from the side of the frame 11 and having an enlarged head as shown in Figure 2. The upper end of the sear is shaped to engage the recess 20 in the hammer 19 to retain the latter in its backward position against the tension of the spring 22. A sear spring 53 is located in a recess in the slot 51 and presses against the sear to force its upper end toward the hammer. A firing edge 54 is formed near the lower end of the sear to receive a firing lug 55 projecting laterally from the upper edge of a sear bar 56 pivotally attached at its rear end to a trigger 57. Said bar is located in a slot in the head of the trigger and its forward end is forced 130

toward the sear as by a sear bar spring 58 located in a recess in the bottom of said slot.

The trigger 57 is pivotally mounted in a slot in a trigger supporting lug 59 projecting downwardly from the under side of the frame 11, and as shown in Figure 2 of the drawings. The trigger is retained in its non-firing position as by means of a trigger spring 60 having its lower end seated in a recess in the upper edge of the trigger and its upper end received on the reduced end of a supporting pin 61.

A cartridge lifting lever 62 is pivotally mounted in a slot 63 extending lengthwise through the forward end of the frame 11 and from the bottom to the top thereof, said slot extending downwardly into the lug 13 and the lower edge of the rear end of the lever being located in said lug. A pin 64 extends across said slot and acts to support the lever. The forward end of the lever has a cartridge receiving recess 65 in its upper edge to receive the cartridges 48 as they are forced backwardly out of the tube 47. A cut-off 66 projects downwardly from the front end of the lever and acts to prevent backward movement of the line of cartridges in the tube 47 when a cartridge is being raised into the upper part of the chamber 42. A spring actuated plunger 67 rests upon a spring seated in a recess in a screw 68 projecting upwardly through the trigger guard plate, and as shown in Figure 1 of the drawings, said spring and plunger being located in a hole through the bottom of the lug 13. It is not intended that this spring shall act to raise the front end of the lever, but merely to retain the lever in its raised position after movement by contact of the lug 34 with an elevating cam 69 on the upper edge 40 of the lever back of the pivot 64. The lever also has a lowering cam 70 formed on its upper edge forward of the pivot 64 by means of which the lever is lowered into position to receive a cartridge when the breech bolt moves forwardly to close the breech.

An extractor 71 is mounted in a slot in the side of the breech bolt in the forward end thereof, the forward end of the extractor having a lip to engage the rim of a cartridge shell 50 and the rear end of the extractor having a knob 72 located in a recess extending inwardly from the bottom of the slot 73.

The knob is held within the recess to retain the extractor in place by means of an extractor retaining plunger 74 seated against a spring 75 located in a recess 76 extending inwardly from the slot in which the extractor 71 is located, and as shown in Figure 6 of the drawings. The other end of the spring presses against a handle retaining plunger 77 having a tapered end to engage an annular groove in the reduced inner end of a breech bolt actuating handle 78 that extends into a recess in the breech bolt, and projects outwardly through a slot 79 opening through

the side of the receiver into the chamber 30 therein. The forward end of the slot is widened to provide an extracting opening 80. The handle 78 is used to move the breech bolt backwardly in its chamber to thereby move the hammer into cocked position when occasion shall require the hammer to be manually cocked. The end of the slot 79 terminates just back of the rear end of the breech bolt, thereby leaving a sight opening 81 through which it may be determined whether or not the hammer is in its cocked or uncocked positions.

A retaining screw 82 projects through the side of the frame 11 into a cutaway portion on the side of the web 35 so that the end of the pin will rest opposite the end of the plunger 33, thereby holding the plunger in place when the receiver, barrel, feed block and magazine tube are removed by an upward lifting movement of the barrel after a holding nut on a bolt projecting from the magazine tube through the forepiece of the stock has been loosened. The barrel being lifted the lip on the receiver is readily disengaged from the flange on the head 14 and the parts just mentioned may then be removed from the frame and the stock.

When the cartridge lifting lever 62 is operated to raise a cartridge into the upper part of the cartridge receiving chamber 42 the rear end of the lever that overlies the forward end of the sear bar 56 depresses this end of said bar, moving the firing lug 55 out of the path of movement of the lower end of the sear, thereby permitting the latter under the influence of the spring 53 to promptly move into position to engage the hammer when the latter is again moved back after a firing operation.

The operation of the gun, briefly described, is as follows, it being understood that the parts are in the positions shown in Figures 1, 2, 6, and 8 of the drawings. The trigger being pulled the lug 55 on the sear bar is pushed forwardly swinging the sear on its pivot and disengaging it from the hammer that is forced forward by the spring 22 into engagement with the firing pin 37, forcing the forward end of the latter into contact with the cartridge in the barrel, thereby exploding the latter. The forces of the explosion cause the breech bolt 29 to be suddenly moved backwardly to the rear end of the chamber 21, in a manner that will be readily understood, carrying the hammer with it which is immediately re-engaged by the sear 50. In this backward movement of the breech bolt the extractor 71 draws the empty cartridge shell from the chamber in the breech of the barrel, the back of the shell at its lower edge striking the ejector 49 that acts to snap the empty cartridge shell from the hold of the extractor and out through the extractor opening 80, in a manner that

will be readily understood by those skilled in the use of firearms of this type.

As the breech bolt moves rearwardly the lug 34 encounters the elevating cam 69 on 5 the lever 62 raising the forward end of the lever and lifting the cartridge thereon into the upper part of the cartridge receiving chamber 42, the plunger 67 under the influence of its spring retaining the lever with 10 its forward end in this raised position with the rim of the shell against the under side of the lips 43.

Immediately upon reaching the back end 15 of the chamber 21 the breech bolt under the force of the spring 31 is moved quickly forward engaging the loading web 35 with the back of the cartridge, thereby moving the latter forward. The nose of the cartridge engages the guide 45 directing said nose upwardly into the opening in the rear end of 20 the barrel, the cartridge rim sliding along underneath the lips 43 until it reaches the opening 44. At this point the rim passes from within the chamber and rides along the upper 25 sides of the lips until the cartridge is fully seated in the barrel.

During forward movement of the breech bolt the lug 34 thereon encounters the lowering cam 70 on the lever, forcing the lever 30 downwardly into position to receive another cartridge from the magazine tube as the line of cartridges in said tube is forced backwardly by the spring in the tube. Backward movement of this line of cartridges was prevented 35 while the lever was in its loading position owing to the presence of the cut-off 66 in front of said line. This terminates a firing action of the gun and the parts are now in position for a repeated action of the same.

40 In accordance with the provisions of the patent statutes I have described the principles of operation of my invention, together with the device which I now consider to represent the best embodiment thereof; but I desire to 45 have it understood that the device shown is only illustrative, and that the invention may be carried out by other means and applied to uses other than those above set out.

I claim:

50 1. A firearm including a stock, a frame enclosed in said stock, a frame head fitted to the upper edge of the frame, a screw projecting through the frame into said head to secure the latter in place, a trigger plate located 55 underneath the stock and spaced from said frame by an intervening part of the frame, a screw projecting through said plate and into the end of the first mentioned screw to secure the plate and frame to the stock, a receiver, 60 a barrel, and firing mechanism mounted on said structure.

2. A firearm including a stock, a frame secured to the upper edge of the stock, a frame head secured to the upper side of the frame at 65 its rear end, a receiver freely removably en-

gaged with the forward end of said head to secure the rear end of the receiver in place, a barrel secured to the front end of the receiver, and firing mechanism supported by said stock and frame.

70 3. A firearm including a stock, a frame secured to the upper edge of the stock, a frame head secured to the upper side of the frame at its rear end, a receiver having a cylindrical chamber with a flange at the end of said chamber engaging a lip on said head to freely removably retain the receiver in place, means for securing the forward end of the receiver, a hammer of cylindrical form fitting said chamber, and cooperating firing mechanism supported by said stock and frame and including a breech bolt slidably mounted in said chamber.

75 4. A firearm including a receiver with means for supporting it, a breech bolt slidably mounted in a chamber in the receiver and having a groove at its outer surface extending lengthwise thereof and across its end, a firing pin located in said groove and having a tail at its end located in the groove across the end of the breech bolt to prevent the forward end of the pin from striking the end of the breech bolt chamber, and firing mechanism supported by said receiver.

80 5. A firearm including a receiver with a barrel secured thereto and means for supporting it, firing mechanism mounted on said receiver and support, a feed block having a cartridge receiving chamber projecting upwardly through a hole in the receiver to guide cartridges to the breech bolt chamber in the barrel, a feed tube projecting into said block to secure it in place, said tube communicating with said chamber, and means for lifting cartridges in said chamber.

85 6. A firearm including a receiver with a barrel secured thereto, firing mechanism mounted on said receiver and support, a feed block having an upwardly projecting cartridge receiving chamber extending through a hole in the receiver to guide cartridges to the breech bolt chamber in the barrel, said block also having a forwardly projecting part fitting the under side of the receiver, and a cartridge feed tube projecting into a hole in the forwardly projecting part and communicating with the chamber in said block.

90 7. A firearm including a receiver with a barrel secured thereto, firing mechanism mounted on said receiver and support therefor, and a feed block including an upwardly projecting cartridge chamber having lips to engage the rim of a cartridge to retain it in the chamber, said lips terminating forwardly to permit the cartridge rim to rise out of the chamber and ride along the top edge of said chamber.

95 8. In combination with the cartridge feed block of a firearm, said block being separately formed from the receiver and fixed against

movement therein, a pivotally mounted lifting lever vertically movable in a slot through the bottom of the chamber in said block, a cut-off extending downwardly from the under side of said lever to govern feed of cartridges into said chamber, and a connection between said lever and the firing mechanism for operation of the former by the latter.

9. A firearm including a frame having a slot in its outer side surface, a receiver mounted on the frame and including a head, a sear mounted in said slot and projecting through an opening in said head, and firing mechanism including a hammer adapted to be engaged by said sear.

10. In combination in a firearm, firing mechanism including a trigger, a hammer and a sear, a sear bar pivotally mounted in a slot in the upper edge of said trigger and projecting forwardly to engage said sear, and a pivotally mounted lifting lever having its end positioned to engage and operate said sear bar.

11. A firearm including a breech bolt having a slot therein, an extractor located in said slot, a plunger engaged with the extractor, a handle projecting into the breech bolt, a plunger engaging said handle, and a spring located between said plungers to force them in opposite directions.

12. A firearm including a receiver having a slot therein, a breech bolt slidably mounted in the receiver and having its end uncovered by the end of the slot forming an opening for examination of the interior of the breech bolt chamber and a hammer resting against said bolt in the forward position of the hammer.

13. In combination with the firing mechanism of a firearm including a breech bolt and an extractor, a loading mechanism including a feed block comprising a cartridge feed chamber, lips at the mouth of said chamber to retain cartridges therein, one of said lips including a projection acting as an ejector in the path of movement of a cartridge shell under the influence of said extractor, and a stock to support said mechanism.

EUGENE G. REISING.
